Primary Examiner — Brett Miller*Assistant Examiner* — Nader Abadir(74) *Attorney, Agent, or Firm* — Adibi IP Group, PC;
Amir V. Adibi; Andrew C. Palmer(57) **CLAIM**

The ornamental design for a cap holder, as shown and described.

DESCRIPTION

FIG. 1 is a front view of a cap holder showing my new design.

FIG. 2 is a back view showing my new design.

FIG. 3 is a left side view thereof.

FIG. 4 is a right side view thereof.

FIG. 5 is a top view thereof.

FIG. 6 is a bottom view thereof.

FIG. 7 is a bottom perspective view thereof.

FIG. 8 is another bottom perspective view thereof.

FIG. 9 is a top-left perspective view showing the cap holder.

FIG. 10 is a top-right perspective view showing the cap holder; and,

FIG. 11 shows the cap holder on a bottle with a bottle cap. The broken lines in FIG. 11 depict portions of the bottle and bottle cap that form no part of the claimed design.

1 Claim, 11 Drawing Sheets(56)
